(57) **CLAIM**

The ornamental design for a hair brush handle, as shown and described.

DESCRIPTION

FIG. 1 is a perspective view of a hair brush handle, showing my new design, in a first environment of use;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the hair brush handle, shown in a second environment of use;

FIG. 10 is a perspective view of the hair brush handle shown in a third environment of use;

FIG. 11 is a perspective view of the hair brush handle shown in a fourth environment of use;

FIG. 12 is a perspective view of the hair brush handle shown in a fifth environment of use; and,

FIG. 13 is a perspective view of the hair brush handle, shown in a sixth environment of use.

The broken lines showing a cord illustrate portions of the hair brush handle and form no part of the claimed design. The remaining broken lines illustrate environmental subject matter only and form no part of the claimed design.

1 Claim, 13 Drawing Sheets
